(57) **CLAIM**

The ornamental design for the floor mat, as shown and described.

DESCRIPTION

FIG. 1 is a front right isometric view of my new floor mat design;

FIG. 2 top plan view thereof;

FIG. 3 is front side view thereof (the rear side view being identical);

FIG. 4 is right side view thereof (the left side view being identical); and,

FIG. 5 is cross sectional view taken along line 5-5 of FIG. 2.

The broken dash line hatching shown in the cross sectional view of FIG. 5 does not form any part of the claimed invention.
